[57] CLAIM

The ornamental design for an editor, as shown and described.

DESCRIPTION

FIG. 1 is a perspective view of a first embodiment of an editor showing our new design;

FIG. 2 is a top plan view of the first embodiment;

FIG. 3 is a left side elevational view thereof, a right side elevational view being a mirror image;

FIG. 4 is a front elevational view thereof;

FIG. 5 is a rear elevational view thereof; and

FIG. 6 is a bottom plan view thereof.

FIG. 7 is a perspective view of a second embodiment of an editor showing our new design;

FIG. 8 is a top plan view thereof;

FIG. 9 is a left side elevational view thereof;

FIG. 10 is a front elevational view thereof;

FIG. 11 is a bottom plan view thereof;

FIG. 12 is a right side elevational view thereof; and,

FIG. 13 is a rear elevational view thereof.
